UNITED STATES PATENT OFFICE

ELWIN L. O'HARA, OF ANTIOCH, CALIFORNIA

SPRAY-TANK AGITATOR

Application filed March 8, 1929. Serial No. 345,422.

This invention relates to spray outfits in which a supply of spraying liquid is carried in a tank and pumped from the tank and discharged under pressure through a spray nozzle.

The solid matter in the liquid has a tendency to settle and must therefore be stirred or agitated at intervals to keep such matter in suspension. One of the major objects of my invention is to provide an agitating means actuated by the liquid itself, in connection with certain very simple parts which causes the agitation to be very effective. I have also arranged for the easy removal of the agitator at any time it needs cleaning.

The provision of the liquid actuated agitator instead of one of a mechanically actuated type, enables me to carry out another object of the invention. This is to eliminate any pump driving engine on the tank and mount the pump directly on the tractor used in hauling the tank so that said pump may be driven from the engine of the tractor. This eliminates the additional cost of a special pump engine and also enables the apparatus to be sold much cheaper than the present type in which the engine is installed as a necessary unit with the pump and wagon. Also the agitator itself is of a very simple and inexpensive nature, likewise enabling the cost of manufacture to be reduced.

These objects I accomplish by means of such structure and relative arrangement of parts as will fully appear by a perusal of the following specification and claims.

In the drawings similar characters of reference indicate corresponding parts in the several views:

Fig. 1 is a side elevation of a spray wagon and tractor connected together showing the tractor operated pump arrangement and the piping connections between said pump and wagon.

Fig. 2 is an enlarged cross section of the tank showing the agitator construction.

Fig. 3 is a sectional plan of the tank.

Referring now more particularly to the characters of reference on the drawings, the numeral 1 denotes the tank of the usual construction and shape, mounted on a pair of

wheels 2 and having a frame 3 adapted at its forward end for connection to the drawbar of a tractor 4 of any desired character. The tractor, as is commonly the case, has a side-drive pulley 5 for driving any desired mechanism, and in the present case is used for driving the pressure pump 6 of standard character such as is commonly used in spray outfits. This pump is rigidly mounted on the tractor at any convenient position at the rear end thereof, and so that the driving pulley of the pump is in line with the pulley 5 so that the two may be connected in driving relation by a belt as shown.

A flexible hose 7 leads to the suction side of the pump from a rigid pipe 8 extending under the tank and connected to the bottom of the same adjacent its ends. The pump discharges into a pressure chamber 9 as is usually provided and from which a flexible hose 10 leads to a rigid pipe 11 secured on the tank. Said pipe at one end leads to the intake side of a pressure regulating valve 12 of common character which is mounted on the tank and at its other end is connected to a length of spray hose 13 on the outer end of which the usual valve controlled spray gun is mounted. From the discharge side of the regulating valve a pipe 14 leads along the top of the tank to adjacent the center of its length and then depends to adjacent the bottom of the tank as shown in Fig. 2. A horizontal section of pipe 15 extends transversely of the tank from the lower end of the pipe 14 and an upwardly projecting capped extension 16 on the opposite end of the pipe 15 leads to the top of the tank. An agitator 17 is turnably mounted with a vertical axis on the pipe 15 between the vertical pipes 14 and 16. This agitator is in the form of a double opposed nozzle element of rotary character as shown with its nozzle ends facing substantially tangent to the arc of rotation and in opposite directions, so that said agitator will be rotated when liquid under pressure is forced through the pipes 14 and 15 and into the agitator.

Under the agitator a horizontal false bottom or lower baffle 18 extends lengthwise of the tank while above said agitator and par-

allel to the lower baffle is another false floor or baffle 19 extending the full width of the tank but terminating short of the ends thereof as shown in Fig. 3. The baffle floor 19 has a circular opening 20 therein of considerable size and disposed axially of the agitator, said opening being provided with opposed notches 21 to receive the vertical pipes and the agitator therethrough so as to enable said agitator and pipe members to be withdrawn as a unit from the top of the tank. To enable this to be done the pipe 14 on top of the tank has a union connection interposed therein as shown at 22. The provision of the capped extension 16 is for the purpose of enabling the agitator to be held in properly centralized relation to the floor orifice and also aids in enabling the same to be removed.

The orificed baffle floor 19 and the solid floor 18 form, together with the agitator, what is in effect a centrifugal pump disposed within the tank below the level of the liquid. This arrangement causes the liquid to be drawn down through the opening 20 with the rotation of the agitator and discharged from between the baffles from both ends. A very efficient agitating and circulating of the liquid and a consequent maintaining of the solid matter in proper suspension in the water is therefore obtained. The pressure regulating valve, as is well known, is for the purpose of relieving the pressure on the pump when the spray nozzles are temporarily shut off and acts to bypass the liquid back to the tank, since the pump itself continues to operate. In the present case instead of simply diverting the liquid back to the tank as is commonly done, I also utilize this bypassed liquid to actuate the agitator, as will be evident.

The provision of this type of agitator enables the tractor mounted pump to be used, since, as will be seen, the only connections between the tractor and the tank are the flexible intake and discharge hoses, and no flexible shafting or other parts of a like nature are necessary to operate the agitator, as would be the case if one of a mechanically operated type were used.

From the foregoing description it will be readily seen that I have produced such a device as substantially fulfills the objects of the invention as set forth herein.

While this construction sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

1. In a spray tank, a rotary agitating nozzle disposed to be below the level of the liquid in the tank, said nozzle comprising opposed

radial discharge pipes and a hub to which they are secured set on a vertical axis, a baffle-floor disposed above the agitator and terminating short of the end-walls of the tank, said floor having an opening concentric with the agitator, and means for circulating liquid from the tank through the agitator under pressure.

2. In a spray tank, a rotary agitating nozzle disposed to be below the level of the liquid in the tank, said nozzle comprising opposed radial discharge pipes and a hub to which they are secured set on a vertical axis, a baffle-floor disposed above the agitator and terminating short of the endwalls of the tank, said floor having an opening concentric with the agitator, a floor under the agitator parallel to the baffle-floor, and means for circulating liquid from the tank through the agitator under pressure.

In testimony whereof I affix my signature.

ELWIN L. O'HARA.
